UNITED STATES PATENT OFFICE.

FRANK E. TREMPER, OF SAN FRANCISCO, CALIFORNIA, ASSIGNOR TO THE SAFETY VAPOR ENGINE COMPANY OF NEW JERSEY.

EXPLOSIVE-ENGINE.

SPECIFICATION forming part of Letters Patent No. 495,281, dated April 11, 1893.

Application filed May 25, 1891. Serial No. 394,056. (No model.)

To all whom it may concern:

Be it known that I, FRANK E. TREMPER, a citizen of the United States, residing in the city and county of San Francisco, State of California, have invented an Improvement in Explosive-Engines; and I hereby declare the following to be a full, clear, and exact description of the same.

My invention relates to the class of explosive engines and it consists in the novel device for producing the spark by which the explosion is effected, and in the novel controlling valve for the cylinder, both of which I shall hereinafter fully describe and specifically point out in the claims.

The general object of my invention is to improve the construction and operativeness of this class of engines.

Particular objects and advantages will be made to appear in connection with the description of my several improvements.

Referring to the accompanying drawings for a more complete explanation of my invention,—Figure 1 is a side elevation of my engine, the upper portion being in section. Fig. 2 is a detail section of the sliding contact rod of the piston and the electrodes. Fig. 3 is a view of the ports in the cylinder, and of the disk valve with its port, said valve being broken away to show the cylinder ports. Fig. 4 is a view of the inlet and exhaust R and S, of the valve chest which correspond to the ports of the cylinder. Fig. 5 is a view showing the location of the valve on the cylinder head. Fig. 6 is a cross-section of the cylinder showing the form preferred of the electrodes. Figs. 7 and 8 show modifications of the electrodes.

A is the engine frame.

40 B is the cylinder.

C is the piston and D is the crank shaft.

The essential novelty of my electrode construction lies in the employment of a spring controlled sliding rod on the piston and a rigid stationary bar extending into the cylinder and lying in the path of the rod on the piston whereby contact is made between them and the electric spark produced by their separation. Further novelty lies in the construction and arrangement of these parts which is as follows:—(See Fig. 2.)

E is an externally threaded casing screwed into the piston. This is preferably lined with asbestos e and in its lower end is seated a washer e' of similar material. Within this casing is fitted a sleeve F which is held therein by a cap f screwed upon the top of the casing, an intervening washer f' being present. Within the sleeve F is fitted and adapted to slide the contact rod G, which is confined 60 therein and its upward movement limited by a collar g on its inner end. The outer end of the rod projects and is provided with a beveled or tapering point g'. Within the sleeve, behind the rod, is the controlling spring H, 65 the upper end of which bears on the head of the rod through the intervention of a washer h of asbestos or other suitable non heat-conducting material. A jam nut I on the casing tightens all these parts to the piston head. It 70 will be seen from this construction that the contact rod G is a spring controlled one and may be pressed inwardly against the spring, and when relieved will be thrown outwardly again. This construction affords, therefore, a 75 practicable and simple yielding or spring controlled contact piece for producing, in connection with the opposing contact or contacts, the electric spark necessary to effect the explosion. A further and particular object in this 80 construction is to remove the spring as far as possible from the action and influence of the heat due to the explosion.

Heretofore in this class of engines it has been found very difficult to maintain the 85 temper of whatever spring may be used, either forming the electrode itself, or controlling said electrode otherwise, because the heat very soon weakens and destroys it; but by my construction it will be observed that the spring 90 being located well within the piston, is removed from the influence of the heat, and this removal can be carried to any extent which experience may find necessary by simply increasing the length of the parts in order 95 to locate the spring as far within the body of the piston as may be necessary to effect its complete isolation.

It may not be necessary in all cases to thoroughly protect the spring by the employment 100 of the outer parts and the intervening non-conductors described, and therefore, in some

cases it would be unnecessary to use the asbestos protectors in the way described. I do not, therefore, confine myself to thus constructing and mounting this spring controlled contact rod G, though it will be found that the construction and arrangement here described is a practicable and simple one.

The opposing electrode or contact may be made in various shapes; thus in Fig. 2 I show 10 the opposing electrode or contact in two parts, one represented by I' and the other by J. One of these, I', passes through the cylinder and has its point bent around upon itself while the other, J, passes through the cylinder 15 and is suitably insulated therefrom, its end coming up close to but terminating short of the end of the part I', thus leaving an opening between the two ends. This opening is directly in the path of the spring controlled 20 contact rod G on the piston, and as the piston moves forward the beveled or tapering point of this rod will enter this space and form contact with the two parts of the stationary or rigid contact bar or electrode I', J, and by its 25 separation therefrom will produce the electric spark. This contact is not a severe one as the spring controlled rod yields upon forming the contact. The object in tapering or beveling the point of the rod G is to produce 30 a scraping contact which tends to keep the surfaces clean and avoids their carbureting, whereby the spark is insured.

In Fig. 6 I show the form of stationary electrodes which I prefer. They are designated 35 by K and L and consist of parallel bars extending through and insulated from the cylinder, their separated inner ends being adapted to receive the tapering or beveled point of the spring controlled rod G between them.

40 In Fig. 7 I have shown another form of stationary rigid electrodes designated by L' and M, one being insulated and the other not. These are separated from each other and extend across the entire cylinder, receiving between them at their centers the point of the 45 spring controlled rod G.

In Fig. 8 other electrodes are shown represented by N and O, one extending from one side of the cylinder and the other from the 50 other side and receiving the point of the spring controlled rod G between them.

The principle of operation is the same in all these forms, namely, the contact being made by means of the sliding spring-controlled 55 rod G introducing its point between rigid or separate contact bars above. All of these forms may be readily put in place without taking off the cylinder head.

In the ordinary forms of electrodes wherein 60 the springs controlling them are outside the cylinder, the electrode guide has a tendency to leak and give trouble. It will be evident that in my construction the contact rod G is quick in action and I can make the spring as 65 heavy as desirable. It will engage the stationary electrodes in a practicable manner and insure a good spark.

P represents my valve by which the entrance and exhaust of the gas takes place. This valve is substantially the same in construction as that shown in the patent to J. W. Eisenhuth, No. 430,310, dated June 17, 1890, upon which it is an improvement in the manner of mounting.

In the use of a disk valve heretofore it has 70 been customary to place it in a horizontal position within the lower portion of the valve chest, and to make in the valve seat within the chest the necessary ports to be controlled by the valve. This construction is disadvantageous in several respects principally in leaving an extra and useless space or chamber in the valve chest above the valve. Also in the difficulty of oiling the valve and also in the tendency to injury on the connected parts 80 due to the explosion upon the top of the valve in the valve chamber. My improvements remedy these defects.

The chief improvement consists in seating the valve directly and flat against the cylinder, either on its side or on its head, and in making the ports which the valve controls, in the cylinder or its head. This arrangement avoids any open chamber in the valve chest, and in reality makes of the chest a kind 95 of carrier for the valve stem and exhaust and gas connections outside.

The explosive chamber is confined entirely to the cylinder. I mount the valve in this position by seating it in a recess in the cylinder or valve chest or carrier and making the outer side of the valve seat itself against the outer wall of this recess so that the outward explosion or compression within the cylinder tends merely to more closely and tightly seat 105 the valve; and in order to provide for the renewal of the wearing surface against which the valve bears I put a stationary ring or die q in the valve chest Q for the valve to seat itself against, which said die may be renewed 110 and another substituted when necessary. Into this valve chest Q opens the inlet pipe R for the gas and the outlet pipe S for the 115 exhaust of the products of explosion. The valve is mounted upon a stem p which extends outwardly and may be driven by a suitable arrangement of gearing from the engine shaft, or better still, and as an improvement thereon, in simplifying the construction and the cost of parts, I prefer to drive this 120 stem by means of a sprocket wheel p' on its outer end driven by a chain p² from a sprocket wheel p³ on the engine shaft below, the two sprocket wheels being relatively proportioned to effect the timely operation of the valve as 125 is usual in engines of this class.

Improvement also lies in the relative arrangement or laying out of the ports in the cylinder and the single port in the valve. The exhaust port in the cylinder is represented by a and the inlet port by a' while the port in the valve is represented by p⁴, (Fig. 3) These ports are so arranged with respect to each other and to the distance through which

the valve travels, and with respect to their relative sizes, as to give what may be called a lead and a lap. A lead is effected by allowing the port in the valve to open the exhaust port just a little before the crank reaches its bottom center so that the products of explosion will begin to exhaust a moment before the piston begins to rise in the cylinder. The lap exists in both the ports of the cylinder and is effected by allowing the port in the valve to get well beyond the exhaust port in the cylinder to cause the valve to fully and thoroughly cover said port before the port in the valve reaches and begins to open the inlet port in the cylinder. This is just before the crank reaches its top center and its advantage is that the inlet port shall not be opened at all before the exhaust port is absolutely and fully closed, and there is no tendency, therefore, for any of the incoming gas to escape through the exhaust port, as might be the case if it were just closing as the gas came in. The lap in the inlet port is effected by allowing the port in the valve to get fully past the inlet port and thereby to cause the valve to fully close it before the compression stroke takes place, so that there will be no gas forced back through said inlet port. The relative arrangement or laying out of these ports is shown in Fig. 3.

Instead of seating the valve within a recess in the valve chest as I have shown, it may be seated in a recess in a boss a^2 formed on the cylinder and seated to place by a suitable ring also on the cylinder or on the valve chest or carrier, as I have shown in Fig. 6. By this arrangement of the valve flat against the cylinder I am enabled to make the two ports in the cylinder itself. I require no open valve chest. The closed valve chest provides for the simple and effective means of introducing the exhaust and gas pipes outside. The valve may be easily lubricated by a suitable oil hole extending to its bearing surface. The face of the valve is protected by this arrangement, and the means for operating the valve by means of the endless chain provide a construction which effects a minimum strain upon the parts. The valve may be easily reseated, scraped and repaired.

In order to insure equal wear and to more securely seat the valve, I can extend the valve stem and place a spring T on same, as shown

by Figs. 1 and 5. The gear may be arranged either side of this spring. This spring may be applied to a valve controlling a single port as well as the double ports shown herein.

Although I have herein shown the valve as seated on the side of the cylinder, I may seat it on the head of the cylinder, as shown in Fig. 5, the valve stem being driven through the intervention of bevel gears U.

Having thus described my invention, what I claim as new, and desire to secure by Letters Patent, is—

1. In an explosive engine, the combination of a sliding spring controlled rod on the piston said rod having a beveled or tapering point, and separated stationary electrodes between which the point of the rod on the piston is adapted to enter and form a scraping contact therewith substantially as herein described.

2. In an explosive engine the casing secured in the piston head and lined with a non-conductor of heat, a sleeve secured within the casing, a sliding contact rod mounted in the sleeve and a spring within the sleeve bearing against the rod, substantially as herein described.

3. In an explosive engine, the combination of the casing mounted within the piston head of the engine, the sleeve in the casing, the sliding contact rod in the sleeve and the spring in the sleeve controlling the movement of the rod and separated rigid or stationary electrodes in the cylinder with which the rod is adapted to form contact, substantially as herein described.

4. In an explosive engine, the combination of the casing in the piston head, the sleeve in the casing, the sliding contact rod in the sleeve, said rod having a beveled or tapering point, the spring in the sleeve controlling the movement of the rod and stationary rigid electrodes in the cylinder between the separated ends of which the point of the rod is adapted to form a scraping contact, substantially as herein described.

In witness whereof I have hereunto set my hand.

FRANK E. TREMPER.
